AUTOMOBILE

Donald G. Weddell, Chicago, Ill.

Application January 14, 1953, Serial No. 23,123

Term of patent 7 years

(Cl. D14—3)

To all whom it may concern:

Be it known that I, Donald G. Weddell, a citizen of the United States of America, residing at Chicago, in the county of Cook and State of Illinois, have invented a new, original, and ornamental Design for an Automobile, of which the following is a specification, reference being had to the accompanying drawing, forming part thereof.

Figure 1 is a perspective view of an automobile, showing my new design.

Figures 2, 3, 4 and 5 are top, side, front and rear views respectively of the automobile shown in Figure 1.

I claim:

The ornamental design for an automobile, as shown.

DONALD G. WEDDELL.
